UNITED STATES PATENT OFFICE.

MAXIMILIAN WEIL, OF NEW YORK, N. Y.

SPRING MOTOR AND ITS INSTALLATION IN PHONOGRAHS.

Application filed July 14, 1920. Serial No. 396,211.

To all whom it may concern:

Be it known that I, MAXIMILIAN WEIL, a citizen of the United States and resident of New York city, in the county of New York and State of New York, have invented certain new and useful Improvements in Spring Motors and Their Installation in Phonographs, of which the following is a specification.

- 10 This invention relates in its more specific application to spring power driving mechanisms for phonographs, and to phonographs embodying such mechanism in a novel combination, although many of the features of 15 the invention are broadly applicable to spring power or equivalent mechanisms regardless in what relation they are employed and what type of apparatus they serve to propel.
- 20 One of the objects of my invention is to provide a spring power mechanism in which the effect of a rupture of the spring element is quickly eliminated without inconvenience, so that even after such rupture the mechanism can be continued in use until such time as replacement of the broken unit can be effected.

By my invention, I provide a compact motor of the above type equipped with 30 means by which the same can be set for satisfactory, efficient operation, even though some of the driving springs are broken or disconnected.

Spring power mechanisms, more particularly mechanisms of the general type installed in phonographs, generally embody two or more coil driving springs arranged side by side along the same axis and connected in succession or in series, the end of 40 each to the end of the preceding one, the purpose of this multi-spring construction being to effect a relatively long running period with one winding, while avoiding the use of a single objectionably large-diameter spring of the combined capacity of the plurality of springs used.

When in the use of such mechanism one of the plurality of springs breaks, the remaining spring or springs will snap to unwound 50 position substantially instantly and rotation of the winding handle will be ineffective to rewind the machine, so that the device becomes useless until repaired by a specialized mechanic. Spring breakages occur without notice in the case of phonograph motors and frequently in the middle of perform-

ances. Furthermore phonographs used in small communities or in camps remote from service stations are frequently disabled by such breakages for prolonged periods pending the arrival of substitute mechanisms or of a specially skilled mechanic capable of making the necessary repairs.

An object of the invention, as embodied in the said multi-spring type of mechanism, 65 is to provide means for conveniently placing in operative relation, the unbroken spring means, upon rupture of any of the plurality of driving spring elements.

This object is preferably carried out by 70 providing a coupling arranged to be readily substituted in the motor for a broken spring, so that the remaining unbroken spring or springs can be wound and will furnish the energy for driving.

The usual spring mechanism for phonograph motors comprises a drum structure and bushing elements coaxially therein, the coil springs being connected at their inner ends, one to each of the bushing elements and at their outer ends to the drum structure. According to one feature of my invention, the coupling to be substituted for a coil spring that is broken or not to be used, 80 will preferably be established between the bushing member corresponding to the broken spring and the adjacent part of the drum structure. By preference this coupling is in the form of a clutch member coaxial with the bushing elements.

Another preferred feature of the invention, more particularly in its application to phonograph motors, is the manual operation of the coupling or clutch member from the exterior of the motor and preferably 95 from the top of the motor board.

The above and other features of my invention may be more fully understood from the following detail description in connection with the accompanying drawings showing a desirable embodiment thereof, in which—

Fig. 1 is a view in longitudinal section of a mechanism embodying my construction mounted in place on the lower surface of a 105 phonograph motor board,

Fig. 2 is a sectional view taken along line 2—2 of Fig. 1,

Fig. 3 is a fragmentary plan view of bushings and of the clutch,

Fig. 4 is a sectional view on an enlarged scale taken along line 4—4 of Fig. 1, and:

Fig. 5 is a detail view of a portion of the operating mechanism.

Referring now to the drawings, I have shown at 1 a fragment of the motor board 5 of a phonograph to the bottom of which is secured the spring motor. This motor is shown by way of illustration as of the two-spring type although the invention is applicable to motors embodying three or more 10 springs. The general features of construction of the motor are preferably identical with those of motors in use. The known elements of the construction comprise a main frame 2 including a pair of standards 3 15 extending downwardly from the motor board when the motor is mounted in position, as shown. Through the standards extends a dead shaft or supporting rod 4. Encircling the rod and floating thereon is the bushing 20 or sleeve 5 upon which is rigidly mounted the gear 6 for transmitting the power to the turn table through mechanism (not shown). A second bushing or sleeve 7 encircles the rod 4, said bushing being longer than bushing 5 and carrying upon its extended end 25 the winding gear mechanism. The details of the latter mechanism are not involved in the present invention and it will, therefore, simply be noted briefly that the winding 30 mechanism comprises a gear 8 secured to bushing 7, the winding torque being transmitted to said gear from a winding handle upon a winding shaft (not shown). The pawl 9 upon the bushing prevents unwinding 35 by its cooperation with a ratchet wheel (not shown) upon the winding shaft.

Encircling the bushings or sleeves and floating thereon is a drum structure 10, comprising a drum or shell element 11, the 40 base 12 of which encircles sleeve 7, and a second similar drum or shell element 13 the base 14 of which encircles sleeve element 5, the two open ends of the drum elements facing each other and being secured together, for instance, by bolts and nuts 15 45 extending through integral outwardly extending flanges 16. The bolts and nuts 15 clamp a metal disk 17 between flanges 16, said disk serving to prevent contact or interference between adjacent sides of the two 50 coil driving springs unit No. 1 and unit No. 2. The driving spring unit No. 1 is coiled within the drum element 11 and secured thereto at its outer end at 18, and the inner 55 end of said spring is secured to the bushing 7 as at 19. The other spring unit No. 2 is similarly secured between the drum element 13 and the sleeve 5. The usual felt stuffers 20 and 21 are provided at opposite 60 ends of the drum encircling the corresponding sleeves to prevent egress of the lubricating grease 22 within the drum.

According to the preferred form of my invention, I provide a clutch 23 situated between the two sleeves or bushings 5 and 7

and axially aligned therewith, preferably having a sleeve fit over rod 4. The clutch is arranged to establish a rigid connection between bushing 7 and the drum 10 when in one position, thereby cutting out of operation the coil spring unit No. 1 and establishing a rigid connection between the winding mechanism and the spring unit No. 2. In a second position the clutch establishes a rigid connection between the sleeve 5 75 and the drum 10, thereby cutting out of operation the coil spring unit No. 2 and establishing a rigid connection between the spring unit No. 1 and the driving gear 6 through which the turn table shaft (not shown) is driven. In the intermediate position shown on the drawings, the clutch element is out of operation and the two springs will function concurrently as in the familiar construction. 85

Preferably the operation of the clutch is effected by a shifting of the supporting rod or dead shaft 4 although shifting means separate and distinct from the supporting rod may be provided. For this purpose I 90 prefer to form the supporting rod of core 24 made of standard stock of somewhat smaller diameter than that commonly in use and to enclose one end of said core in a snugly fitting sleeve 25 which may be made of a standard size of metal tubing, the 95 said sleeve being rigidly secured upon the rod by means of a pin 26. The clutch element 23 which is preferably freely rotatable upon the rod core may readily be 100 slipped over the other end of the said core after the sleeve 25 is applied, whereupon a second sleeve 27 may be slipped over the latter end of the core and pinned in place as at 28. By preference the distance between adjoining ends of sleeves 25 and 27 is slightly greater than the width of clutch 23 to avoid binding. By this construction 105 it will be seen that the clutch element will be shiftable with the rod either towards the right or toward the left. It will, of course, be understood that the rod core with the two encircling sleeves at opposite ends constitutes but a preferred illustrative manner in which the object can be carried out, of 110 effecting a shifting of the clutch substantially as a unit with the rod and other expedients may be employed for this purpose. For instance, the rod might be made from 115 stock of the outer diameter of the sleeve and be reduced at one end, a single sleeve being slipped over said reduced end and secured thereto after the clutch is placed in position on the rod.

The clutch is preferably provided with a 125 pair of longitudinal integral keys 28 and 29 at diametrically opposite points, the separating disk 17 having a central opening embracing said clutch and provided with notches or keyways 30 and 31 for accommo-

dating said keys. The keys 28 and 29 project beyond opposite ends of the clutch member preferably as at 32 and 33 to form clutch teeth for cooperation with corresponding clutch teeth 34 and 35 formed at the ends of the sleeves or bushings 7 and 5 adjacent the clutch. The latter teeth are preferably formed around the entire periphery of the sleeves or bushings and are 10 tapered at their outer ends as at 36 to permit entry of teeth of member 23 between corresponding teeth on the sleeves 5 or 7 depending on the direction of shifting, without likelihood of end to end contact or butting. The teeth 32 and 33 on the clutch member may also be tapered if desired as at 37 to still further reduce the likelihood of butting. The length of the keys upon the clutch is such that the keys remain in the 20 grooves or keyways 30 and 31 in disk 17, at all times, whether the clutch is shifted to the extreme right or to the extreme left. The maximum diameter of the clutch should be no greater than, and is preferably less 25 than the outer diameter of the sleeves or bushings in order to avoid interference with the inner convolutions of the encircling coil springs. Obviously the clutch teeth of member 23 might be formed separate and distinct from the keys 30 and 31 and a different number of keys or clutch teeth might be used.

Preferably operating means for the clutch or coupling member is provided, readily accessible from the upper surface of the motor board. This operating means by way of illustration comprises a turn button 38 upon the motor board connected by a pin 39 extending vertically through the motor board 40 and in the same plane as supporting rod 4, an eccentric 40 being rigidly secured to said pin near the lower end thereof and substantially in the horizontal plane of the supporting rod. The eccentric 40 fits into a corresponding opening in an eccentric plate 41, the said plate having pivoted thereto by means of a screw 42 a coupling member 43, the reduced end 44 of which fits into a corresponding socket 45 formed in the end 46 of the shifting rod core 24. A set screw 46 extending through an opening 47 in socket 45 serves to establish a connection between the coupling member and the end of the shifting rod.

I prefer to form a plurality of circumferential grooves 48 in the reduced end 44 of the coupling member to permit variation of the distance between the motor and the operating pin, this adjustment being provided 60 to dispense with the need for mounting the parts upon the motor board with great accuracy.

Encircling the pin 39 and upon the upper surface of the motor board there is an indicating dial 49 and a spacer sleeve 50 en-

closes the pin 39 and extends between said dial and the eccentric 40 to prevent substantial upward and downward movement of the turn button with its associated rod and eccentric. A coil compression spring 51 encircles the sleeve 50 and presses at one end downwardly upon the eccentric and at the other end upwardly upon the disk, thereby producing the requisite friction to prevent inadvertent shifting of the turn button from any position in which it may be set. The various elements of the operating member, it is clear, can be produced at small expense from standard gauges of rods and tubing.

The indicating dial 49 for the specific motor shown will have three indications as, for instance, "Unit No. 1," "Unit No. 2," and "Units Nos. 1 and 2" at 52, 53 and 54 respectively, and rotatable with the turn button there is preferably provided an indicating pointer 55 which by way of convenience may have thereon the word "Operating" or some equivalent word. The designations 52, 53 and 54 upon the indicator disk 90 are so disposed that when the pointer is moved to the position 52, the clutch will be in cooperation with the sleeve 5, so that the device will be operating on unit No. 1 in accordance with the indicator reading and when the pointer is opposite unit No. 2 the clutch will be in cooperation with the opposite sleeve 7 cutting out unit No. 1. For the intermediate position of the pointer, the clutch will be in neutral position midway between the sleeves 5 and 7 and the device will be set for operation upon both spring units.

In use, the phonograph motor may, if desired, be initially set in neutral position, as shown on the drawings, so that the operation proceeds with both springs operating in series, the pointer being in the intermediate position shown in Fig. 4. As soon as a break or rupture occurs in either of the spring units Nos. 1 and 2, the energy stored in the motor will immediately be released and the spring will snap to unwound position against the drum.

Assuming that units No. 2 has broken, to set the device for operation, the turn button is grasped and rotated until the pointer registers with the indication 52 corresponding to operation of unit No. 1, the unbroken spring. By this operation the eccentric 40 will be rotated from the intermediate position shown in Fig. 5 in the direction of the arrow, thus urging the eccentric plate 41 toward the left and through the coupling 43, the shifting rod 4 will also be drawn toward the left, carrying with it the clutch 23, the teeth 33 of which enter into mesh with the clutching construction 35 at the end of the sleeve or bushing 5, the keys 28 and 29 on the clutch remaining in cooperation with the notches 30, 31 in the disk 130

17. The clutch in this position establishes a rigid connection between the sleeve 5 and the disk 17, thereby bringing about, in effect, a mechanical short-circuit about the broken 5 spring unit No. 2. When winding torque is now applied through the winding handle (not shown), the same will be transmitted through the sleeve 7, unbroken spring unit No. 1, the drum member 11, the disk 17, the 10 keyways or notches 30, 31, the keys 28, 29, the clutch 23, the sleeve 5 and the driving gear 6, which latter is held against rotation both in winding and when the motor is stationary by the brake (not shown). 15 The unbroken spring is held against unwinding in the usual manner by the restraining action of the pawl and ratchet of the winding mechanism. When the brake mechanism is released, the single driving spring 20 will, therefore, operate the turn table through the gear wheel 6.

The user, of course, does not know when a rupture occurs whether it is unit No. 1 or unit No. 2 that has become inoperative. 25 If, as above assumed, the spring unit No. 2 breaks but the user rotates the turn button to position 53, "Unit No. 2 operating", that is, for operation of the broken spring winding, of course, cannot take place since the 30 clutch would then be connected about the operative spring unit No. 2 and the motor would offer no resistance to rotation of the winding handle. The user being thus apprised that the setting of the button is not 35 the appropriate one will then turn the button to the only other position, that of, "Unit No. 1 operating" and the device will function as above set forth.

Should the spring unit No. 1 break in 40 operation, the clutch will be moved toward the right by shifting the turn button to the position 53 in which the pointer 55 comes into registry with the designation "Unit No. 2 operating", thereby moving the clutch 45 member towards the right into cooperation with the clutch 7. The winding of the unbroken spring unit No. 2 can now be effected by rotation of the winding handle, the winding torque being transmitted from 50 the sleeve 7 through clutch teeth 34 to clutch 23 and from the keys 28, 29 thereon, through grooves or keyways 30, 31 to disk 17, thence through drum member 13 to the outer end of unbroken spring unit 2. The inner end of 55 the spring is held against rotation by the sleeve 5, the braking mechanism holding against rotation the gear 6 that is rigid with said sleeve. Winding therefore proceeds. The unbroken spring is now held 60 against unwinding by the brake mechanism at one end and at its other end by the pawl and ratchet on the winding mechanism, the latter spring end being connected to the pawl and ratchet through the disk 17, clutch 65 23 and sleeve 7.

If, with spring unit No. 1 broken, the turn button be moved for operation of unit No. 1, no torque can be transmitted beyond sleeve 7, as the spring connected to the latter is broken.

Thus when in use either spring breaks, the motor can be restored to operative conditions by simple rotation of the turn button upon the motor board, whereupon the motor can be wound and its functioning will 75 proceed through the remaining unbroken spring until such time as the motor can be repaired or replaced.

The motor can thus be set for operation by any inexpert person, even by a child, 80 there being no occasion to touch or even to inspect the motor. It will be understood that, if desired, automatic means might be provided for shifting the clutch.

Although the clutch member is completely 85 inclosed within the drum and the operating member extends through the drum to the exterior, yet the lubricating grease will not escape therefrom since no auxiliary opening is used for the connection from the clutch 90 to the exterior operating mechanism but this connection is effected through one of the passages in the drum through which the supporting rod 4 extends.

The spring 51 of the operating mechanism 95 offers resistance, as heretofore noted, to the rotation of the turn button and, therefore, also to the displacement of the eccentric 40 and of the clutch 23. The clutch is, therefore, held by this means against undesired 100 shifting from the position in which it is set. Of course, other means might be provided for this purpose.

Although the motor can be operated to advantage according to the method above 105 indicated, it is preferable not to set the clutch in the neutral position when the motor is new, or at any other time, but to place it from the outset into cooperation with either sleeve 5 or sleeve 7 so that the motor operates at all times on only one spring, the unused spring not being used at all and being maintained in perfect condition, to be cut into operation only when the first spring breaks down. My invention thus constitutes 110 a selector by the use of which a choice can be exercised as to which spring or springs are to be kept in use, and by which a unit of the motor is kept in reserve.

It will, of course, be obvious that my invention might be carried out in a construction in which it would be possible to use only one of the springs at a time, there being no neutral position for operation with both springs concurrently. This idea might be 115 carried out in a simple manner by reducing the distance between the ends of the sleeves or bushings 5 and 7 or by lengthening the clutch teeth on the member 23.

Of course, by the use of only one spring 120

the running time of the phonograph motor will be only one-half of that where both springs are used concurrently. However, with the springs in use, this time is more than sufficient to play the largest record and since it is an easy matter, and in the case of many users a matter of habit to wind the motor after the playing of each record, no inconvenience results from the shorter running time.

It will thus be seen that by means of a simple modification of certain details of a phonograph motor otherwise of standard construction, including the usual centrifugal governor (not shown). I achieve the desirable results above noted. My invention is carried out in a phonograph motor embodying any usual form of frame and the drum and the spring construction used in practice are not modified in any particular. The only changes made from standard constructions are, the stamping of the usual sheet metal disk with a pair of notches in the central opening, the substitution for the plain supporting rod of a rod composed of a core made from standard stock with sleeves from standard tubing slipped over opposite ends thereof and pinned in place thereon retaining therebetween a clutch member which is formed at small expense from a unitary metal piece, one end of each of the sleeves or bushings being formed with integral clutch teeth, but otherwise of standard construction. The operating mechanism connecting the shifting rod to the top of the motor board as seen is made at small expense from standard gauge stock.

Although I prefer to employ the specific construction shown, in which the clutch 23 is so connected with respect to the drum by means of the disk 17 that no substantial relative rotation takes place between the clutch and the drum, the clutch being mounted for free rotation upon the supporting rod, it will be understood that a reverse arrangement would be included in the scope of my invention, in which the clutch would be rotatable as a unit with the supporting rod, the drum being normally rotatable with respect to the clutch. The latter arrangement is less desirable than that of my preferred form because the driving mechanism, in operation, is compelled to rotate the supporting rod, which further involves loss of power through friction, since each spring urges the rod laterally against its bearings.

Although the invention has been shown and described as applied to a power unit of the two-spring type, it will be understood that the idea can be readily applied to drums embodying three or more springs, in such manner that any one of the plurality of springs can be eliminated from operation either when intact or when ruptured, or that any one of said plurality of springs can be

maintained in operation, the others being eliminated from operation.

No increase in length or diameter of spring motors results from embodying my selector mechanism therein, since in the preferred form the clutch means is disposed within the gap or gaps between successive bushings or sleeves and the supporting rod serves as a transmission to the clutch means from the manual operating means external of the motor. The motor with my selector mechanism embodied therein is a single self-contained unit that can be applied to the phonograph with the same facility as motors that do not embody this invention. The operating means is operatively connected to the motor by the simple process of tightening set-screw 46 upon coupling element 44.

The above description has been limited to the preferred application of my invention to phonograph motors. The invention is, however, useful in a wide range of applications. For instance, multi-spring motors are useful for operating signal apparatus and the use of my invention in such application, whether manually set upon breaking of a spring, or operated automatically responsive to such breakage, is particularly beneficial.

The invention is useful in spring motors generally, regardless of the type of construction or the number of springs, and it will be understood that in its broader aspects, the invention might be embodied in any spring construction having associated therewith means for substituting a relatively rigid connection for a section of the spring mechanism, whether such spring section is intact or broken. It will also be apparent that this rigid connection might be embodied in various forms of couplings other than the clutch arrangement shown.

I claim:

1. In apparatus of the character described, in combination, a driving spring mechanism, and means for substituting a substantially rigid connection for a section of said spring mechanism.

2. In apparatus of the character described, in combination, a driving spring mechanism, coupling means associated with said mechanism, and means for operating said coupling means to establish a mechanical power transmitting connection about a section of said mechanism.

3. In apparatus of the character described, in combination, a driving spring means, a coupling device associated with said means to establish a connection in lieu of a section of said spring means, and manually operated means for connecting said coupling device at will into operative or inoperative position.

4. In apparatus of the character described, in combination, a drum, coil spring

- means therein having a winding end and a power delivery end, a coupling device co-operating with said spring means and between said ends for establishing a rigid connection about a section of said spring means, and means for shifting said coupling means to operative or inoperative position.
5. In apparatus of the character described, in combination, a drum, coil spring means therein having a winding connection near one end and having means for delivering its stored energy near the other end, a coupling device within said drum for establishing a rigid connection about a section of said spring, and manually operated means extending outside of said drum for shifting said coupling device at will to operative or inoperative position.
10. In apparatus of the character described, in combination, a driving coil spring means having a winding end and a power delivery end, a coupling device co-operating with said spring means and between the ends thereof, and means for setting said device for establishing a rigid connection around any one of a plurality of sections of said spring means.
15. The combination of claim 6 in which the coupling device is manually operated and has a neutral or inoperative position in addition to the plurality of operative settings.
20. In apparatus of the character described, in combination, a driving coil spring having a winding connection at one end and a power delivery connection at the other end, and a coupling device co-operating with said spring means and operable to couple a part of said spring means intermediate the ends thereof with one of said end connections.
25. In apparatus of the character described, in combination, a driving coil spring having a winding connection at one end, and a power delivery connection at the other end, and a coupling device co-operating with said spring means and having one inoperative setting and two operative settings, said coupling device serving in one of said latter settings to couple a part of said spring means intermediate the ends thereof with said winding connection and in the other operative setting to couple said power delivery connection to a part of said spring means intermediate the ends thereof.
30. In apparatus of the character described, in combination, a driving coil spring, a drum enclosing said spring and having a winding connection for said spring at one end, and a power delivery connection at the other end, a coupling device within said drum adapted to cooperate with said spring means, and manually operated means extending outside of said drum to move said coupling device for joining a part of said
35. means intermediate the ends thereof with one of said end connections.
40. In apparatus of the character described, a coil driving spring mechanism and coupling means arranged axially within said mechanism, and means for operating said coupling means to establish a mechanical power transmitting connection about a section of the driving spring means.
45. A spring power unit comprising a plurality of driving springs connected in series, and means for establishing a rigid coupling connection between the ends of any one of said springs.
50. A spring power unit comprising a rigid winding connection at one end and a rigid power delivery connection at the other end, a plurality of driving springs between said ends, rigid connecting means for joining said springs in series, and means for establishing a rigid coupling between two of said rigid connections.
55. A spring power unit comprising a rigid winding connection at one end, a rigid power delivery connection at the other end, a plurality of driving springs between said ends, rigid connecting means for joining said springs in series, a coupling member within said unit, and manually operated means for moving said coupling member to rigidly join the rigid connections at opposite ends of any one of said springs.
60. A spring power unit comprising a rigid winding connection at one end, a rigid power delivery connection at the other end, a plurality of driving springs between said ends, rigid connecting means for joining said springs in series, coupling means within said unit, and manual means for operating said coupling means to maintain in operation any one of said springs and to rigidly join the rigid connections at the ends of the remaining spring means.
65. A spring power unit comprising a plurality of axially aligned shell members, a plurality of core members, one axially in each shell member, a plurality of springs coiled about said core members and within said shell members, the ends of said springs being secured to the corresponding core and shell members, the core at one end of the unit having a winding connection and that at the other a power delivery connection, rigid connections between adjoining ends of successive springs, and means for establishing a rigid connection between any said core and the corresponding shell for cutting out of operation the spring included therebetween, while preserving the operativeness of the unit.
70. A spring power unit having a winding end and a power delivery end, a bushing at the winding end, a drum member encircling the same, a bushing at the power delivery end, and a drum member encir-
75. 80. 85. 90. 95. 100. 105. 110. 115. 120. 125. 130.

- clinging the latter, means establishing a driving connection between said drum members, springs coiled about said bushings and secured thereto at one end and attached to said members at the other end, and means for establishing a rigid connection in lieu of the spring connection between any bushing and the corresponding drum member.
18. A spring power unit comprising a drum, a pair of bushings one at each end of said drum, winding means connected to one said bushing, power delivery means connected to the other said bushing, a coil spring secured at one end to one said bushing and at the other to said drum, a second coil spring secured at one end to said drum and at the other to the other bushing, a coupling element within said drum operable to establish a rigid connection between said drum and either of said bushings, and manual means extending outside of said drum for operating said coupling element.
19. A spring power unit comprising a drum structure and a plurality of floating bushings extending along the axis thereof, a plurality of springs within said drum structure, one corresponding to each bushing and secured thereto at one end, each spring being connected at its other end to said drum structure, said springs being connected in series, clutch means axially aligned with said bushings, means securing said clutch means against substantial rotation relative to the adjacent part of said drum means, and means for shifting said clutch means to clutch any of said bushings.
20. In a spring power unit of the type which includes a drum, a pair of axially aligned bushings floatingly disposed therein, a pair of coil springs corresponding one to each bushing and secured thereto at one end, the opposite ends of each said spring being secured to said drum, and a disk secured within said drum and between said springs, a clutch member aligned with said bushings, and means holding said clutch member against substantial rotation with respect to said disk, while permitting displacement thereof axially in either direction for clutching one or the other of the bushings adjacent thereto.
21. The combination of claim 20 in which the clutch member has clutching teeth at opposite ends thereof, and in which corresponding teeth are provided at the ends of the bushing members adjacent to said clutch member teeth.
22. In a spring power unit of the type which includes a drum, a pair of axially aligned bushings floatingly disposed therein, a pair of coil springs corresponding one to each bushing and secured thereto at one end, the opposite end of each of said springs being secured to said drum, and a disk secured with-
- in said drum and between said springs; the combination therewith of a clutch member between said bushings and aligned therewith, said clutch member extending through a central opening in said disk, a key on said clutch member extending into a corresponding notch in said disk, said key projecting beyond the end surfaces of said clutch member to form clutch teeth, and corresponding clutch teeth in the end surfaces of said bushings adjacent to said clutch member.
23. The combination of claim 22 in which there are two diametrically opposite keys upon the clutch members fitting in corresponding notches in the disk member, said keys being formed integral with said clutch member.
24. A spring power unit comprising a drum, a pair of axially aligned bushings floatingly disposed therein, a pair of coil springs corresponding one to each bushing and secured thereto at one end, the opposite end of each of said springs being secured to said drum, a disk secured within said drum and between said springs, a clutch member between said bushings axially aligned therewith and keyed to said disk, the greatest diameter of said clutch member being no greater than the diameter of said bushings whereby the springs will be kept out of contact with said clutch member.
25. A spring power unit comprising a drum, a pair of axially aligned bushings floatingly disposed therein, a pair of coil springs corresponding one to each bushing and secured thereto at one end, the opposite end of each of said springs being secured to said drum, a disk secured within said drum and between said springs, a quantity of lubricant within said drum, a clutch member keyed in a central opening in said disk and adapted to be shifted for clutching either said bushings, and means extending from said clutch member to the exterior of said drum for shifting the former said drum, and shifting means being constructed and arranged relative to each other to prevent escape of lubricant from said drum.
26. A spring power unit comprising a drum, a pair of axially aligned bushings floatingly disposed therein, a pair of coil springs corresponding one to each bushing and secured thereto at one end, the opposite end of each of said springs being secured to said drum, a clutch member within said drum between said bushings and axially aligned therewith and adapted to establish a rigid connection between said drum and one of said bushings, and a shifting part for said clutch member, said shifting part extending from said clutch member axially through one end of said unit.
27. A spring power unit comprising a drum, a pair of axially aligned bushings floatingly disposed therein, a pair of coil

5 springs corresponding one to each bushing and secured thereto at one end, the opposite end of each of said springs being secured to said drum, a clutch member within
 10 said drum between said bushings and axially aligned therewith, said clutch having two operative settings, one in clutching engagement with each of said bushings, an inoperative setting out of contact with said bushings, and a shifting part for said clutch member operable from the exterior of said power unit.

15 28. Apparatus of the character described comprising a shiftable supporting rod, having clutch teeth carried thereby intermediate its ends, a pair of bushings on said rod and at opposite sides of said clutch teeth and having corresponding clutch teeth, an enclosing drum, a pair of coil springs, one corresponding to each bushing and secured thereto at one end, the opposite end of each spring being secured to said drum, and means connecting said supporting rod clutch teeth with respect to said drum, to prevent
 20 substantial relative rotation.

25 29. The combination of claim 28 in which the length of the clutch teeth extends parallel to said rod.

30 30. A spring power unit comprising a drum, a pair of axially aligned bushings floatingly disposed therein, a pair of coil springs corresponding one to each bushing and secured thereto at one end, the opposite end of each of said springs being secured
 35 to said drum, a shiftable rod extending axially through said bushings, a clutch member mounted for rotation with respect to said rod and between said bushings, means preventing substantial displacement of said clutch member longitudinally with respect to said rod, and means to prevent substantial rotation of said clutch member with respect to said drum.

40 31. A spring power unit comprising a drum, a pair of axially aligned bushings floatingly disposed therein, a pair of coil springs corresponding one to each bushing and secured thereto at one end, the opposite end of each of said springs being secured to said drum, a shiftable supporting rod extending axially through said bushings, a clutch member rotatably mounted on said rod and between said bushings, said rod having a diameter at one end smaller
 45 than the bore in said clutch member, to permit slipping the latter upon said rod, the rod having rigid therewith a portion of larger diameter to form a stop for limiting shifting of said clutch member along the rod in one direction, a sleeve slipped over said end of said rod and secured thereto to form a stop against shifting of said clutch member in the other direction, and means to prevent substantial rotation of said clutch member with respect to said drum.

50 32. Apparatus of the character described comprising a shiftable supporting rod, a clutch member rotatably mounted thereon, sleeve members surrounding said rod and secured thereto at opposite sides of said clutch member to form shoulders for preventing substantial shifting of said clutch member along said rod, a pair of bushings floatingly supported upon said sleeves, clutch teeth upon said clutch member, teeth upon the adjacent ends of said bushings for cooperation therewith, an enclosing drum, a pair of coil springs, one corresponding to each bushing and secured thereto at one end, the opposite end of each spring being secured to said drum, and means connecting said clutch member with respect to said drum, to prevent substantial relative rotation.

55 33. In a spring power unit of the type which includes a drum, a pair of axially aligned bushings floatingly disposed therein, a pair of coil springs corresponding one to each bushing and secured thereto at one end, the opposite end of each said spring being secured to said drum, and a disk secured within said drum and between said springs; the combination therewith of a supporting rod for said unit, extending through said bushings and slidably therein, and a clutch member rotatably mounted upon said rod and between said bushings and shiftable with said rod, said clutch member having keys cooperating with said disk, and clutch teeth in said bushings for cooperation with said keys.

60 34. In a spring power unit of the type which includes a drum, a pair of axially aligned bushings floatingly disposed therein, a pair of coil springs corresponding one to each bushing and secured thereto at one end, the opposite end of each said spring being secured to said drum, and a disk secured within said drum and between said springs; the combination therewith of a slidable rod extending axially through one of said bushings and having a toothed clutch part between said bushings and under control of said rod, said clutch part being keyed to said disk, there being teeth upon said bushings for cooperation with those on said clutch part.

65 35. The combination of claim 33 in which the keys extend beyond the end surfaces of said clutch member, and in which the diameter of the bushings is greater than the greatest diameter of said clutch member.

70 36. A spring power unit comprising a drum, a pair of axially aligned bushings floatingly disposed therein, a pair of coil springs corresponding one to each bushing and secured thereto at one end, the opposite end of each of said springs being secured to said drum, a clutch member within said drum between said bushings and axially aligned therewith, a disk secured within said

drum at right angles to said bushings and between said springs, a key upon said clutch member parallel to said bushings and extending into a corresponding notch in said 5 disk, said key extending beyond the end surfaces of said clutch member to form clutch teeth, corresponding clutch teeth in the adjacent ends of the bushing members, means for shifting said clutch member, the length 10 of said key being greater than the range of shift in each direction, whereby the clutch member remains keyed to the disk in all settings.

37. The method of operating a spring 15 motor of substantially the construction specified in claim 36 with the clutch member shifted into cooperation with one of the bushings, thereby forming a rigid connection about the corresponding spring, and 20 shifting the clutch member into cooperation with the other bushing upon breaking of the spring in use.

38. In a phonograph, in combination a motor therefor, secured therein and including 25 a driving spring mechanism, coupling means associated with said mechanism, and means accessible in the assembled phonograph for operating said coupling means to establish a rigid power transmitting connection about 30 a section of said spring mechanism.

39. In a phonograph of the type which includes motor-supporting means, a spring motor secured thereto and including a drum structure and a plurality of coil springs 35 therein connected in series, bushings in said drum structure, said springs being connected to said bushings at one end and to said drum structure at the other; the combination therewith of means in said drum structure for establishing a rigid connection between any said bushing and the adjacent part of the drum structure, eliminating the corresponding spring from the mechanical circuit, a shifting rod for said coupling 45 means extending axially from said drum structure, and means manually operable from the exterior of said phonograph for actuating said coupling means through said shifting rod.

50 40. In a phonograph of the type which includes a motor board, a spring motor secured to the lower surface thereof and including a pair of standards, a horizontal supporting rod carried by said standards, a plurality of bushings floatingly mounted 55 upon said rod, a drum structure about said bushings, and springs connecting said bushings to said drum structure; the arrangement of said rod for limited sliding with 60 respect to said drum structure, and the combination therewith of a coupling member slidably with said rod and adapted to make a rigid connection between one of said bushings and the adjacent part of the drum, a 65 button upon the upper surface of said motor

board, and means extending through said board and connected to said button and to said rod for transmitting a shifting impulse from said button to said rod.

41. The combination of claim 39 in which 70 coating indicating designations are provided upon a stationary part of the phonograph and the manual operating means, to show which spring or springs are in use and which idle.

42. In combination, a phonograph, a spring motor mounted therein and including a drum structure, a plurality of axially aligned bushings floating therein, and driving 80 springs one for each bushing, connecting the corresponding bushing to said drum structure, the driving springs being arranged in series, clutch means arranged axially between successive bushings, shifting means therefor projecting axially from the drum 85 structure, said clutch means having an inoperative and a plurality of operative settings, manual operating means for said shifting means accessible from the exterior of the phonograph, and means for retaining 90 said clutch means against accidental displacement from any of its settings.

43. In combination, a phonograph having a motor board, a spring motor mounted upon the lower surface thereof, and including 95 a drum structure, a plurality of axially aligned bushings floating therein, and driving springs one for each bushing, connecting the corresponding bushing to said drum structure, the driving springs being arranged in series, clutch means arranged axially between successive bushings, shifting means therefor projecting axially from the drum structure, said clutch means having an inoperative and a plurality of operative settings, manual operating means for said shifting means accessible from the upper 100 surface of said motor board, and spring means for frictionally resisting displacement of said operating means, thereby retaining said clutching means against accidental displacement from any of its settings.

44. An operating means for a spring selector mechanism of the type provided with a shifting rod, said operating means comprising a rod to extend vertically through a motor board and having a turn button at its upper end, an eccentric upon the lower end of said rod, an eccentric plate having an opening in which said eccentric fits, a coupling piece pivoted to said plate, said coupling piece being adapted for connection to the shifting rod of the selector mechanism.

45. The combination of claim 44 in which 115 the turn button has a pointer rotatable therewith for indicating for which spring or springs the motor is set to operate.

46. A spring power unit comprising a 120 drum structure, a supporting shaft therefor,

a plurality of bushings floatingly mounted upon said shaft, a plurality of springs within said drum structure, one corresponding to each bushing and secured thereto at one end, each spring being connected at its other end to said drum structure, said springs being connected in series, clutch means upon said shaft and between said bushings, means securing said clutch means against substantial rotation relative to one of said shaft and drum structure, and means for shifting said clutch means to clutch any of said bushings.

47. In a spring power unit of the type which includes a drum, a pair of axially aligned bushings floatingly disposed therein, a pair of coil springs corresponding one to each bushing and secured thereto at one end, the opposite ends of each said spring being secured to said drum, and a disk secured within said drum and between said springs; the combination therewith of a clutch member aligned with said bushings and arranged to establish a clutching connection with either of said bushings, said bushings having clutch teeth with tapered ends, and said clutch member having teeth adapted to enter into mesh between said tapered teeth.

48. A spring motor comprising in combination, a frame, a power plant mounted thereon and comprising a plurality of coaxially arranged coil springs, a single winding gear means for delivering energy to all of said springs, a transmission to be driven by all of said springs, a power transmitting member disposed intermediate the ends of said power plant, and means for shifting said power transmitting member to remove some of said springs from operative connection.

49. A spring motor comprising in combination, a frame, a power plant mounted thereon and comprising a plurality of coaxially arranged coil springs, winding gear means for delivering energy to all of said springs, a transmission to be driven by all of said springs, a power transmitting member cooperating with said power plant intermediate the ends thereof, and means for shifting said power transmitting member longitudinally of said power plant to set the motor for operation upon one half of said power plant when said transmitting member is at one side of neutral position

and upon the other half thereof when at the other side of neutral.

50. A spring motor comprising in combination, a frame, a power plant mounted thereon and including a pair of coaxially arranged coil spring elements, a single winding gear means for delivering energy to both of said spring elements, a transmission to be driven by both of said spring elements, a power transmitting member disposed half way between the ends of said power plant, and means for displacing said power transmitting member through a limited range longitudinally of said power plant, said transmitting member being arranged with respect to the elements of said power plant in such manner that when moved to one extreme position, it will render inoperative one of said spring elements and when moved to the other extreme position, it will render inoperative the other said spring element and when in intermediate position both of said spring elements will be connected for driving operation.

51. A spring motor comprising in combination, a frame, a power plant mounted thereon and comprising a pair of coaxial coil spring sections arranged side by side, toothed members near adjacent ends of said sections, a rod extending longitudinally of said power plant, a toothed coupling member thereon and shiftably arranged, said coupling member when in one extreme position meshing with one of said toothed members and establishing a continuous power connection between said winding gear and said turn table shaft through one of said spring sections and excluding the other from operation and when in the other extreme position establishing a similar power connection through the other of said spring sections and excluding the first.

52. In apparatus of the character described, in combination, a plurality of spring-power generating elements, non-power generating transmitting elements, and means for bridging one or more of said first elements with corresponding transmitting elements.

Signed at New York, in the county of New York and State of New York, this 13th day of July, A. D. 1920.

MAXIMILIAN WEIL.
